PROTECTIVE HOUSING FOR COILS

Wade H. Reichard, Rochester, N. Y., assignor to
General Railway Signal Company, Rochester,
N. Y.

Application September 11, 1935, Serial No. 40,112

5 Claims. (Cl. 175—361)

This invention relates to electric coils, and more particularly to a protective housing for car-carried receiver coils of the type employed in railway train control systems and the like.

5 In railway train control systems, a receiver coil on a magnetic core structure is carried by the locomotive in rather close proximity to the track rails in order to be inductively affected by current in the track rails. Such coils are exposed to moisture, oil and other deteriorating substances and are continuously subjected to the jars and vibrations of the train, all of which tend to alter the coil characteristics by causing broken wires, short circuits, and the like. It has also 10 been found that as these coils must be mounted directly above the rails, various loose objects along the trackway such as stones and the like are thrown against the coils with considerable force thereby puncturing or gradually wearing 15 away the outer covering of the coils and causing considerable damage to the windings thereof. These coils are also occasionally exposed to rather high temperatures such as caused by steam emitted from the locomotive cylinders or 20 the like which likewise may damage or deteriorate the coil insulation.

In view of the above and other considerations, it is proposed in accordance with the present invention to provide a protective housing for coils 25 which prevents damage to the coil wires or insulation by shocks or vibration, which is not easily damaged by abrasive action thereon and which is moisture, oil and heat repellent. More specifically, it is proposed to provide a coil housing 30 of rubber in a pliable form which is treated to resist abrasion and deteriorating substances, and which rubber housing resiliently suspends the windings of the coil around a magnetic core, whereby to prevent shocks and vibrations of the 35 core from being transmitted to the coil. It is also proposed to provide such a coil housing which is conveniently removable from its supporting magnetic core.

Other objects, purposes and characteristic features of the present invention will be apparent as the description thereof progresses, during which reference will be made to the accompanying drawing, in which:—

Fig. 1 is an elevational view of a complete 50 receiver coil arranged in accordance with the present invention and shown in its normal car-carried position above a railway track rail.

Fig. 2 is an enlarged elevational view of the coil shown in Fig. 1 with a part thereof shown 55 in section.

Fig. 3 is an elevational view of the coil shown in Fig. 2, the partial section in Fig. 2 being taken substantially on line 2—2 of Fig. 3.

In the usual type of railway train control systems, receiver coils on magnetic cores are carried in front of the first pair of wheels of the locomotive directly above each track rail. In this manner, the alternating train control current flowing in the rails produces a flux which is collected by the magnetic core to pass through the receiver coils in a manner to induce current therein which conditions the car-carried train control apparatus in accordance with forward traffic conditions.

In Fig. 1 of the accompanying drawing, such a magnetic receiver structure is illustrated as including a laminated horizontal core 4 extending transversely above a track rail 5 illustrated in section. The extending ends of the core 4 are magnetically joined to laminated pole pieces clamped between upright supporting plates 6 by through bolts 7, the ends of the laminated core 4 being also clamped between the plates 6 by through bolts 8. Inasmuch as it is considered advisable to electrically insulate the core pieces from the supporting plates 6, an insulating plate 9 is provided between each of the plates 6 and the laminated core and pole pieces, and likewise, suitable means may be employed such as insulated sleeves to electrically insulate the body portions of the through bolts 7 and 8 from the core pieces. Hanger members 10 are attached to the upper ends of plates 6 such as by welding, and the hanger members 10 are adapted to mount the magnetic structure thus formed on the railway vehicle.

A receiver coil is provided on the central portion of the core 4 which is constructed in accordance with the present invention as more clearly shown in Fig. 2 and Fig. 3. Referring to Fig. 2, a ring-shaped coil 12 is wound on a suitable arbor or the like to the required number of turns and of suitable insulated wire and taped or otherwise retained in its cylindrical shape of the proper dimensions. Lead wires 13 are suitably attached to the ends of the winding, and the coil may be impregnated with suitable insulating compound in the usual manner.

The coil 12 is entirely surrounded by a housing formed by oppositely arranged molded rubber cases 15 and 16. The cases 15 and 16 are molded from mechanical-grade rubber in a pliable state, as, for example, these cases 15 and 16 may be molded of the same material and pliability as that employed in treads of high grade pneumatic

tires. In other words, a pliable abrasion-resistant material is employed in the molded cases 15 and 16 which is impervious to moisture and is not rapidly deteriorated by oil or heat.

5 The cases 15 and 16 each have outer cylindrical surfaces and are substantially E-shaped in cross section as shown in Fig. 2, the centers being provided with aligning through openings receiving and closely fitting around the substantially square core 4. In this manner, substantially half of the coil 12 is received by a hollow cylindrical interior of each of the cases 15 and 16, the two cases 15 and 16 jointly forming an enclosure for the complete coil 12 as may be seen 10 in the sectional view of case 16 in Fig. 2. The cases 15 and 16 are of course assembled from the respective ends of coil 12 so that their inner ends abut as shown, and these abutting ends are carefully sealed with a suitable rubber cement or 15 the like.

20 The cases thus form a complete enclosure for the coil 12 wherein a rather thick sleeve of pliable rubber is formed separating the inner surface of the coil 12 from the core 4, and a 25 similar outer sleeve is formed of substantially the same thickness surrounding the outer surface of the coil 12. The closed ends of the cases 15 and 16 are provided with integral webs 15¹ and 16¹ extending vertically throughout the 30 diameters of the cases, and as may be seen in Fig. 3, these webs 15¹ and 16¹ are wider than the core 4.

35 The inner portions of the cases 15 and 16 which surround a core 4 as well as the outer portion surrounding the coil 12 are provided with aligning horizontal holes receiving through bolts 18, whereby the two cases 15 and 16 are assembled around the coil 12. In the illustrated form shown in Fig. 3, four through bolts 18 are provided through the inner portion of the cases 15 and 16 which bolts extend through the web 15¹ and 16¹, the heads of the lower two of these bolts being held by a strap 19 resting in a recess in the web 16¹, while nuts 20 on these four inner bolts 18 engage similar straps resting in recesses 40 in the web 15¹. In a similar manner, two upper and two lower bolts 18 through the outer portion of the cases 15 and 16 pass through the webs 15¹ and 16¹, the heads of these bolts and nuts 20 45 threaded thereon being held by respective arcuate straps 21, while the outer side portions of the cases 15 and 16 are clamped by four shorter through bolts 18, the heads of these bolts and their nuts 20 being held by respective longer 50 arcuate straps 22. In this arrangement, the through bolts 18 not only retain the two cases 15 and 16 in their assembled position but also 55 serve to reinforce the sides of these rubber cases 15 and 16.

60 A metal bushing 24 is molded into the upper portion of the web 16¹ of the right hand case 16 to thereby form a passage communicating with the interior of the coil housing for bringing out the lead wires 13. The bushing 24 is provided with inner and outer flanges, the outer flange being flush with the surface of the web 16¹ and shaped as shown in Fig. 3 to receive the heads of the four upper through bolts 18. A metal conduit fitting 25 is clamped against the outer surface of the bushing 24 by stud bolts 26 65 passing through horizontally extending ears on the fitting 25 and threaded into bushing 24.

70 The hole in bushing 24 is preferably tapered as shown in Fig. 2, and a convenient means for 75 closing this opening around the lead wires 13

is provided by a pliable rubber plug 27 having spaced holes receiving the lead wires 13. A rigid disc 28 of insulating material also having holes receiving the lead wires 13 is provided between the plug 27 and the fitting 25 whereby the pliable plug 27 is compressed when assembling the fitting 25 to thoroughly seal the opening around the lead wires 13. The use of the rubber plug 27 however is optional as the opening around the lead wires 13 may be sealed with 10 suitable thermo-plastic insulating compound.

15 The completely enclosed coil is detachably retained on the core 4 by bolts 30, one passing through the center of each of the webs 15¹ and 16¹ of the rubber cases 15 and 16 and through 20 holes in the core 4. The rubber webs 15¹ and 16¹ are protected from the heads of bolts 30 and nuts 31 threaded thereon by enlarged washers 32.

25 An electric coil has thus been provided which is particularly adapted for use in train control systems wherein the coils are continually subjected to adverse conditions. The windings of the present coil are resiliently suspended around the magnetic core whereby the shocks and vibrations to which the core is continually subjected are not transmitted to the windings, but rather these shocks and vibrations are substantially absorbed by the resilient rubber sleeve separating the coil from the core.

30 The present coil is further protected by a complete housing of resilient material which not only protects the windings from external shock due to flying stones and the like but also offers a maximum of resistance to the abrasive action of objects engaging the coil housing. A coil constructed in accordance with the present invention has the further advantage of being entirely 35 impervious to moisture and other substances which might deteriorate or alter the characteristics of the windings, and the coil housing is not rapidly deteriorated by oil, heat or any other various substances or conditions ordinarily 40 encountered along a railway system. The present coil is also a separate unit detachable from its magnetic core to thereby permit such coils to be 45 replaced on the same core structure and assembled apart from the magnetic core.

50 The above rather specific description of one form of the present invention is given solely by way of example, and is not intended, in any manner whatsoever, in a limiting sense. It is to be understood that various modifications, adaptations and alterations may be applied to meet the requirements of practice without in any manner departing from the spirit or scope of the invention, except as limited by the appended claims.

55 What I claim is:—

1. In a car-carried receiver coil, a magnetic core, windings around the core and spaced therefrom, oppositely arranged pliable molded rubber cases completely enclosing the windings and having each an integral sleeve portion separating the windings from the core and an outer portion covering the winding, whereby to resiliently 60 suspend the windings around the core and protect the windings.

65 2. In a car-carried receiver coil, a magnetic core, windings around the core, oppositely arranged pliable molded rubber cases completely enclosing the windings, and means sealing the 70 cases around the windings, said cases having integral abutting sleeve portions separating the windings from the core whereby to resiliently suspend the windings around the core.

75 3. In a housing for train control receiver coils,

- two cylindrical molded cases of pliable mechanical-grade rubber having closed outer ends and open abutting inner ends, through bolts for assembling the two cases around the coil, and integral abutting center portions in the cases having aligning apertures for receiving a magnetic core.
4. In a housing for train control receiver coils, two cylindrical molded cases of pliable mechanical-grade rubber having outer closed ends and open abutting inner ends, means for assembling the two cases around the coil, integral abutting center portions in the cases having aligning apertures for receiving a magnetic core.
5. In a housing for train control receiver coils having magnetic cores, two molded cases of mechanical-grade rubber for completely enclosing the coil, integral sleeves in the cases separating the coil from the magnetic core, a metal bushing molded into one of the casings, and means for attaching a conduit to the bushing.
